COUPLING MECHANISM

Charles H. Tomlinson, Mansfield, Ohio, assignor
to The Tomlinson Coupler Company, Mans-
field, Ohio, a corporation of Ohio

Application March 1, 1932, Serial No. 596,017

20 Claims. (Cl. 213—76)

My invention relates to couplers for cars and couplers for train lines such as air, steam, water and electricity.

The objects of my invention are to provide,

5 A car coupler of novel construction and operation.

A combined car, fluid pressure and electric coupler of novel construction.

An improved car coupler in which the coupling mechanism on two coupled heads may be operated simultaneously to the uncoupled position from either head or from a point in either car.

An improved coupler for the train lines of a train of cars cooperating with the car coupler and in which two coupled heads will hold the train lines coupled so long as the car couplers remain coupled and will automatically uncouple when the car couplers have parted a predetermined distance but will remain coupled and permit a predetermined amount of movement between the car coupler heads without uncoupling so long as the car couplers remain coupled.

20 An improved coupler for the train lines of a train of cars which will automatically part when the coupled cars have separated a predetermined amount.

An improved coupler device in which two coupled heads are held tightly coupled and are constantly urged into tighter coupled relation.

30 My invention resides in the new and novel construction, combination and relation of the various parts hereinafter described and shown in the drawings accompanying this specification.

In the drawings:—

35 Fig. 1 is a top view of my improved car coupler also adapted for coupling fluid pressure and electric lines.

Fig. 2 is a vertical view in partial section on the line 2—2 of Fig. 1.

40 Fig. 3 is a horizontal view of the head portion only in partial section taken through the longitudinal horizontal axis of the coupler and with the locking mechanism shown in uncoupling position.

Fig. 4 is a sectional view of two heads similar to that shown in Fig. 3 in coupled relation.

45 Fig. 5 is a top plan view of a locking latch or coupling bolt which I employ.

Fig. 6 is a horizontal sectional view on the line 6—6 of Fig. 2 showing a detachable form of connection for the steam lines.

50 Fig. 7 is a modification of the connection shown in Fig. 6 and differs by being provided with check valves.

Fig. 8 is a front or face view in elevation of my car coupler showing an arrangement of connec-

tions for air, steam and electric train lines, the arrangement being a modification of that shown in Fig. 14.

Fig. 9 is a top plan view of my coupler arranged for connecting train lines and to be used in conjunction with the coupler shown in Fig. 1 or with any other type of coupler.

Fig. 10 is a vertical sectional view of the train line coupler shown in Fig. 9 in partial section on the line 10—10 of Fig. 9 and showing my invention suspended beneath a car coupler of the Janney type.

Fig. 11 is a horizontal view in partial section taken on the line 11—11 of Fig. 10.

Fig. 12 is a face view of the train line coupler 15 head showing the air and steam connections.

Fig. 13 is a horizontal view in partial section on the line 13—13 of Fig. 10 and shows a yielding support for the coupler.

Fig. 14 is a face view of the car coupler shown 20 in Fig. 2 with the fluid pressure connectors mounted on the upper and lower faces of the coupler head.

In the preferred embodiment of my invention I employ a body member 1 provided with an enlarged head portion 2 and an extended portion 3. The head is provided with a projecting pin 4 having parallel sides and a beveled end and projecting through the opening 5 in the face of the counterpart coupler head. The opening 5 is 25 provided with an inwardly projecting wall 6 which engages with the several side faces 7 of the pin 4 or is provided with a very small clearance such that the engagement of the pin 4 with the wall 6 will prevent buckling or bending of the 30 heads relative to each other.

If the coupler is to be used merely as a car coupler then the face of the coupler will appear perfectly plain and without the connectors for steam and air as shown in Figs. 1 and 2.

40 Mounted in supporting guides 14 and 15 is a transversely slideable bolt or latch 16 having an enlarged head 17 with reduced portion 18. The latch is yieldably held in its advanced position by means of the spring 19 and held against advancement in the uncoupled relation beyond a predetermined amount by the pin 19' engaging the guide 14.

45 The locking latch is provided upon its front face with a tapered portion 20 which when engaged by the pin of the counterpart coupler will retract the latch as the pin of the counterpart coupler advances and when the two coupler faces are in contact an opening 21 in the inner face of the pin 4 will be opposite the latch 16 and the 50 55

latch 16 will then advance under action of the spring 19 until it projects into the opening 21.

Fig. 3 shows a single head in which the latch 16 has been withdrawn to its unlocking position 5 while in Fig. 4 two heads are shown in coupled relation with the latch in its coupled relation to the opposite head.

It will be noted that the locking latch 16 is provided with a tapered face 22 opposite the 10 face 20 and it will be noted that the pin 4 is provided in the recess 21 with a face 23 which is engaged by the face 22 on the locking latch and is beveled in like manner. The beveled faces 22 and 23 cooperating tend not only to hold the 15 coupler heads with their faces in tight relation but will take up wear to a certain degree thus maintaining the heads tight through a period of time.

From the description thus given it will be seen 20 that the construction of the head is very simple and the coupled heads will be held in not only tight relation but the latch will tend to urge the heads into even tighter relation and the pins 4 cooperating with the recesses in the opposite head 25 will tend to prevent vertical, lateral and buckling movement of the heads.

In order to uncouple two heads without the 30 necessity of operating the locking latches 16 independently of each other in the two heads I provide a lever 24 pivoted at 25 and which projects from the coupler head for manual operation and also engages with the latch 16 of the opposite head when coupled. A lever 26 is pivoted to the lever 24 and to the lug 27 on the locking latch such 35 that when the lever 24 is operated to uncouple, the latch 16 in the corresponding head will be moved with the lever 24 and thus the locking levers 16 on the two heads will be operated simultaneously from one head.

40 If desired the heads may be equipped with air uncoupling mechanism consisting of an air cylinder 28 having a piston 29 therein held in a retracted position by means of the spring 30 and also having a pin 31 which will engage with the 45 lever 24. A pipe 32 leads from the cylinder to a source of air supply as for instance the reservoir pipe 51 (Fig. 1) and a control valve 32' may be mounted in the pipe 32 and at any convenient position on the car such that when the control 50 valve is opened air will enter the cylinder 28 and advance the piston such that the pin 31 will operate to move the lever 24 to its uncoupling position and with it the locking latches 16.

Thus the unlocking of the two heads may take 55 place manually from one coupler head or through pneumatic means from any position in one car. The rearwardly projecting portion 3 is made hollow to receive a draft spring 33 and a stem 34. I have shown a bearing 35 pressed into position 60 in the member 3 against relative movement therewith and I have also shown a gland 36 screwed into position in the end of the member 3. Interposed between the inner faces of the members 35 and 36 is the draft spring 33. Positioned with- 65 in the bearing 35 and the gland 36 is the member 34 which has a threaded end portion 37 with a ball attachment 38 for connection to the ball anchorage 39, which in turn is secured to the car body 40. The member 34 slides longitudinally in 70 the members 35 and 36 such that whenever the head is moved longitudinally from its normal or uncoupling position the spring 33 will be compressed.

75 The coupler head thus described may be yield- ingly supported from the car body by means of a

horizontal yoke 41 yieldingly secured to the car body by means of the springs 42 (see Patent 1,585,948 issued May 25, 1926 to C. H. Tomlinson).

If desired the car coupler heads thus described may be equipped with connections for the air which may consist of an attachment 43 which may be secured to the top surface of the coupler head by means of bolts 44 and which has chambers 45 and 46 which are connected to substantially form a single chamber and from which 10 projects the coupling 47 and 48. There is also a chamber 49 with the air connection 50.

From the combined chambers 45 and 46 projects the pipe 51 which may be termed the reservoir line and from the chamber 49 projects the 15 pipe 52 which may be termed the brake pipe.

A connecting device 53 for steam may be secured to the lower face of the coupler head by means of the bolts 54 passing through the lugs 55 as shown in Fig. 14. 20

Fig. 6 shows a horizontal section of the afore- 25 said steam connecting device and comprises a body member 56 having a chamber 57, a composition packing ring 58 such as bakelite held in place by a gland nut 59, and a reciprocating connection 60 which engages with the member 58 on the counterpart head. Spring 61 is biased to advance the connection 60 and movable with the member 60 is a packing 62 held in position by means of the threaded flange 63 secured to the 30 member 60. The opening 64 is threaded to receive the steam line 65.

A modified form of the steam connection shown in Fig. 6 is set forth in Fig. 7 and has in addition to the elements set forth in Fig. 6 a reciprocating member 66 which is held in its advanced position by the spring 67 and has a valve 68 engaging with the composition ring 58 thus closing the passage when the head is not coupled. The coupling device is also provided with a reciprocating mem- 40 ber 69 which is provided with a valve 70 for clos- 45 ing off the chamber 57 by means of the spring 71 when the head is not coupled. The operation of the device shown in Fig. 7 is the same as that in Fig. 6 excepting that when the two heads come 45 together the members 66 and 69 on the two heads are engaged and forced inwardly thus opening the check valves and as the heads continue to come together the member 60 will engage with the member 58 on the opposite head until they 50 are finally together thus completing the steam connection between the two heads. The pipe 65 is attached to the threaded opening 64.

With the steam coupling shown in Fig. 6 it is 55 apparent that a valve must be placed in the line 65 at some point which may be operated manually or automatically.

The train line connectors 43 and 53 may be mounted upon the upper and lower faces of the coupler head as shown in Fig. 14 or may be dove- 60 tailed or recessed into the coupler head as shown in the train line coupling of Fig. 12 and held by bolts.

Fig. 8 is a front view of the above car coupler equipped with air connector 50' and steam connector 53' and electric connector 13 or connectors 50' and 53' may both be for air or for steam as desired. 65

By modifications of the head above described I am able to adapt it only to the coupling of steam, 70 air and electric lines upon cars already equipped with car couplers such as of the Janney type or with other types and it may be arranged to maintain the train lines in coupled relation even though there be longitudinal movement between 75

the heads of the car couplers or between the cars themselves and to open automatically if the car couplers are uncoupled and separated. In such arrangement (see Figs. 10 and 11) I provide a 5 coupler having a head portion 100 and a projecting hollow portion 101 provided with a shoulder 102 and a removable gland 103 held in place by bolts 104 and having a face 105, a draft spring 106 positioned between the faces 102 and 105 with 10 interposed washers 107.

Extending longitudinally through the interior 15 of the member 101 is a member 108 having secured to the outer end a portion 109 by means of the rivet 110 and having a recessed portion 111. To the inner end of the member 108 is secured 20 a loop-shaped member 112 having a transverse opening 113 and secured by means of the rivet 114.

Secured to the car coupler 115, which may be 25 of the Janney or other type, is a downwardly projecting bracket or anchorage 116 to which is secured by means of the rivets 117 a pin 118 and secured to the lower end of the pin 118 is a retainer 119 projecting into the recessed portion 111. The construction of the recessed portion 111 and retaining member 119 is such that the coupler 25 will have substantially universal movement relative to the member 118.

By supporting the train line coupler from the 30 car coupler, the adjustment of the moving parts on the train line coupler may be made much closer as the relative movement to be compensated for is that between the car coupler heads 115 as later explained.

35 The two heads are locked and held in coupled relation substantially the same as in the car coupler above described and each head is provided with a projecting pin 120 having a side recess 121 and a tapered surface 122. The head is also provided with a recess 120' to receive the pin 120 on a counterpart head. There is also provided a transversely movable locking latch 123 having enlarged head 124 held and guided by the member 157 and a reduced projection 125 held 40 and guided by the member 156 and a spring 126 to advance the latch. The advance of the latch 123 beyond a predetermined point while the head is uncoupled is checked by a pin 125' engaging the back guide 156. Enlarged portion 124 is provided with the tapered face 127 to engage with the projecting pin 120 on the cooperating head to retract the latch when the two heads come together. The latch is also provided with the tapered surface 128 which engages with the tapered surface 122 on the cooperating pin thus not 45 only holding the two heads in a tightly coupled relation but constantly urging the heads into tighter coupled relation and also taking up wear.

In order to automatically uncouple two heads 50 should the car couplers 115 become uncoupled intentionally or accidentally I provide a lever 129 pivoted at 130 and having one portion extending into the slot 113 and another portion extending into a slot 131 of the locking latch 123.

55 It will be quite evident that with the members 108-109-112 fixedly secured to each other and fixedly secured to the anchorage 116 against longitudinal movement relative thereto that as the head 100 is moved forward it will be advanced 60 relative to the members 108-109-112 and if such relative movement is sufficient the member 112 will engage with the lever 129 and rotate the same upon its pivot 130 causing the opposite end of the lever which is positioned in socket 131 in the locking lever to engage the wall at one end

of the socket and move the locking latch to its unlocking position and it is evident that if two heads are coupled together and the uncoupling of the car couplers 115 should take place and the couplers move away from each other that the same action will take place with respect to the train line couplers as just described for the single coupler causing the latches in the two heads to be moved automatically to their uncoupling position when the separation of the cars or the couplers 115 has reached a predetermined distance.

I prefer to have the face of the train line coupler in advance of the face of the car coupler as for instance the line 132 represents the face of the train line coupler in Fig. 10 and the line 15 133 represents the pulling face of the car coupler 115. Thus when two cars are coupled the heads 100 together with the projecting portion 101 will be moved rearwardly in a longitudinal direction relative to their respective supports 108-109- 20 112, thus the lever 129 will not be in contact with the member 112 as shown in Fig. 11 and therefore there will be no danger of the heads being uncoupled due to a predetermined amount of longitudinal movement between the heads of 25 the couplers 115.

I prefer to make the cross section of the member 101 and of the member 112 rectangular thus assisting to hold these two parts in a predetermined relation against relative rotation although 30 they may be made of a circular cross section.

Projecting from opposite sides of the member 101 are lugs 134 and which have mounted thereon yielding supports 135 which comprise telescopic members 136 and 137 yieldingly held in 35 extended position by the spring 138 and having the interengaging flanges 136' and 137' respectively to limit movement in one direction. The lugs 134 are secured to the yielding supports 135 through the medium of the headed stud 139.

The coupler 115 is provided with downwardly projecting and spaced lugs 140 and secured to each lug is a pivotally mounted member 141. Each member 135 is provided with an eye portion 142 and the members 135 are secured to the members 141 by means of the thru-bolt 143. It will be evident from the construction that if the coupler body tends to move rearwardly with respect to the car coupler 115 that it may do so through the yielding construction of the members 135 and at the same time such members will yieldingly support the coupler head; also, there will be enough clearance between the parts such that the head may move sideways relative to the car coupler 115 a limited amount and the head may move 40 upwardly with respect to the coupler 115 due to the telescopic action of the members 135.

The train line connections to the head may be variously arranged, for instance as shown in Figs. 9, 10 and 12 the arrangement provides for 45 a detachable connecting device 144 and which is also shown in Fig. 10 in section and may comprise chambers 145 and 146 connected together by the cross chamber 145' and having front connections 147 and 148 and a pipe connection 149 leading therefrom and which may be termed the reservoir air connection. The member 144 may also have a chamber 150 with a front connection 151 and a pipe connection 152 as shown 50 in Figs. 9 and 13.

The head may also be provided with an insert steam-connecting device 153 which is provided with a single chamber and may be constructed along the lines of that shown in Fig. 6 or Fig. 7 only arranged for inserting within the head as 55 70 75

shown or bolted to the outer surfaces thereof. A pipe 154 leads therefrom.

It will be apparent that in place of the M. C. B. type of coupler being employed as shown in Fig. 5 10 the car coupler shown in Fig. 1 may be employed.

It will also be apparent that modifications may be made from those disclosed but I wish to be limited only by my claims.

10 I claim:—

1. A car coupler comprising in combination a coupler head having a substantially flat face at right angles to the longitudinal axis of the coupler and a pin projecting from the face at one side of the center and a recess in the face at the other side of the center, the pin and recess arranged to cooperate with a recess and pin respectively in a similar coupled head, the pin having an opening in its inner face and one face of the opening spaced from the coupler face being beveled, a sliding locking member movable transversely to the longitudinal axis of the coupler and positioned adjacent the inner surface of the front wall of the head, the locking member having a portion projecting into the recess in the coupler face and the projecting portion having a beveled face to be engaged by the end of the pin of the cooperating coupler to retract the locking member, a spring arranged to advance the locking member which is provided with a beveled face to engage with the beveled face in the opening in the pin of the cooperating head to lock the heads together, the last mentioned beveled surfaces cooperating to draw the faces of the couplers tightly together, a pivoted uncoupling lever having one end projecting without the head and the other end projecting into the opening in the pin to engage the locking member on the cooperating head to move the locking member to its unlocking position, a link connecting the said lever and the locking member to move the locking member to its unlocking position to release the pin on the cooperating head and a longitudinally projecting means from the head and means at the end of the projecting means to secure the coupler to a support on the car.
2. A car coupler comprising in combination a coupler head having a substantially flat face and a hollow pin projecting from the face at one side of the center and a recess in the face at the other side of the center, the pin and recess arranged to cooperate with a recess and pin respectively in a similar coupled head, the pin having an opening in its inner face communicating with the recess in the pin and one face of the opening spaced from the coupler face being beveled, a sliding locking member movable transversely to the longitudinal axis of the coupler, the locking member having a portion projecting into the recess in the coupler face and the projecting portion having a beveled face to be engaged by the end of the pin of the cooperating coupler to retract the locking member, a spring arranged to advance the locking member which is provided with a beveled face to engage with the beveled face in the opening in the pin of the cooperating head to lock the heads together, the last mentioned beveled surfaces cooperating to draw the faces of the couplers tightly together, unlocking mechanism associated with the head and arranged to act upon the locking members on two coupled heads to move the locking members to the unlocking position simultaneously, and a longitudinally projecting means from the head and means at the end of the projecting means to secure the coupler to a support on the car.
3. A car coupler comprising in combination a coupler head having a substantially flat face at right angles to the longitudinal axis of the coupler and a pin projecting from the face at one side of the center and a recess in the face at the other side of the center, the pin and recess arranged to cooperate with a recess and pin respectively in a similar coupled head, the pin having an opening in its inner face, a sliding locking member movable transversely to the longitudinal axis of the coupler and positioned adjacent the inner surface of the front wall of the head, the locking member having a portion projecting into the recess in the coupler face and the projecting portion having a beveled face to be engaged by the end of the pin of the cooperating coupler to retract the locking member, a spring operating to advance the locking member which is adapted to enter the opening in the pin of the cooperating head to lock the heads together, a pivoted uncoupling lever having one end projecting without the head and the other end projecting into the opening in the pin to engage the locking member on the cooperating head to move the locking member to its unlocking position, a link connecting the said lever and the locking member to move the locking member to its unlocking position to release the pin on the cooperating head and a longitudinally projecting means from the head and means at the end of the projecting means to secure the coupler to a support on the car.
4. A car coupler comprising in combination a coupler head having a substantially flat face and a hollow pin projecting from the face at one side of the center and a recess in the face at the other side of the center, the pin and recess arranged to cooperate with a recess and pin respectively in a similar coupled head, the pin having an opening in its inner face communicating with the recess in the pin, a sliding locking member movable transversely to the longitudinal axis of the coupler, the locking member having a portion projecting into the recess in the coupler face and the projecting portion having a beveled face to be engaged by the end of the pin of the cooperating coupler to retract the locking member, a spring arranged to advance the locking member which is adapted to enter the opening in the pin of the cooperating head to lock the heads together, unlocking mechanism mounted on the head and arranged to act upon the locking members on two coupled heads to move the locking members to the unlocking position simultaneously, and a longitudinally projecting means from the head and means at the end of the projecting means to secure the coupler to a support on the car.
5. A car coupler comprising in combination a coupler head having a substantially flat face and a hollow pin projecting from the face at one side of the center and a recess in the face at the other side of the center, the pin and recess arranged to cooperate with a recess and pin respectively in a similar coupled head, the pin having an opening in its inner face communicating with the recess in the pin, a sliding locking member movable transversely to the longitudinal axis of the coupler, the locking member having a portion projecting into the recess in the coupler face and the projecting portion having a beveled face to be engaged by the end of the pin on the cooperating coupler to retract the locking member, a

and means at the end of the projecting means to secure the coupler to a support on the car.

3. A car coupler comprising in combination a coupler head having a substantially flat face at right angles to the longitudinal axis of the coupler and a pin projecting from the face at one side of the center and a recess in the face at the other side of the center, the pin and recess arranged to cooperate with a recess and pin respectively in a similar coupled head, the pin having an opening in its inner face, a sliding locking member movable transversely to the longitudinal axis of the coupler and positioned adjacent the inner surface of the front wall of the head, the locking member having a portion projecting into the recess in the coupler face and the projecting portion having a beveled face to be engaged by the end of the pin of the cooperating coupler to retract the locking member, a spring operating to advance the locking member which is adapted to enter the opening in the pin of the cooperating head to lock the heads together, a pivoted uncoupling lever having one end projecting without the head and the other end projecting into the opening in the pin to engage the locking member on the cooperating head to move the locking member to its unlocking position, a link connecting the said lever and the locking member to move the locking member to its unlocking position to release the pin on the cooperating head and a longitudinally projecting means from the head and means at the end of the projecting means to secure the coupler to a support on the car.

4. A car coupler comprising in combination a coupler head having a substantially flat face and a hollow pin projecting from the face at one side of the center and a recess in the face at the other side of the center, the pin and recess arranged to cooperate with a recess and pin respectively in a similar coupled head, the pin having an opening in its inner face communicating with the recess in the pin, a sliding locking member movable transversely to the longitudinal axis of the coupler, the locking member having a portion projecting into the recess in the coupler face and the projecting portion having a beveled face to be engaged by the end of the pin of the cooperating coupler to retract the locking member, a spring arranged to advance the locking member which is adapted to enter the opening in the pin of the cooperating head to lock the heads together, unlocking mechanism mounted on the head and arranged to act upon the locking members on two coupled heads to move the locking members to the unlocking position simultaneously, and a longitudinally projecting means from the head and means at the end of the projecting means to secure the coupler to a support on the car.

5. A car coupler comprising in combination a coupler head having a substantially flat face and a hollow pin projecting from the face at one side of the center and a recess in the face at the other side of the center, the pin and recess arranged to cooperate with a recess and pin respectively in a similar coupled head, the pin having an opening in its inner face communicating with the recess in the pin, a sliding locking member movable transversely to the longitudinal axis of the coupler, the locking member having a portion projecting into the recess in the coupler face and the projecting portion having a beveled face to be engaged by the end of the pin on the cooperating coupler to retract the locking member, a

5 spring arranged to advance the locking member which is adapted to enter the opening in the pin of the cooperating head to lock the heads together, unlocking mechanism mounted on the head arranged to cooperate with the locking members on two coupled heads to move the locking members to the unlocking position simultaneously, pneumatic means acting upon the unlocking mechanism to move the unlocking mechanism and means located on the car to control air to the pneumatic means.

10 6. A car coupler comprising in combination a coupler head having a substantially flat face and a hollow pin having a beveled end surface projecting from the face at one side of the center and a recess in the face at the other side of the center, the pin and recess arranged to cooperate with a recess and pin respectively in a similar coupled head, the pin having an opening in its inner face communicating with the recess in the pin, a sliding locking member movable transversely to the longitudinal axis of the coupler, the locking member having a portion projecting into the recess in the coupler face and the projecting portion to be engaged by the beveled end surface of the pin on the cooperating coupler to retract the locking member, a spring operating to advance the locking member which is adapted to enter the opening in the pin of the cooperating head to lock the heads together, unlocking mechanism mounted on the head and having means arranged to act upon the locking members on two coupled heads to move the locking members on the two heads to the unlocking position simultaneously.

15 7. A car coupler comprising in combination a coupler head having a substantially flat face and a pin projecting from the face to one side of the center and a recess in the face to the other side of the center, the pin and recess arranged to cooperate with the recess and pin respectively of a similar coupled head to prevent relative lateral and angular movement of the heads, the pin having a pocket, a transversely sliding locking member, the locking member having a portion projecting into the recess in the coupler face to be engaged by the pin on the cooperating coupler to retract the locking member, a spring arranged to advance the locking member which is adapted to enter the pocket in the pin of the cooperating head and engage its wall to lock the heads together, unlocking mechanism movably mounted on the head and arranged to act upon the locking members on two coupled heads to simultaneously move the locking members to the unlocking position.

20 8. A car coupler comprising in combination a coupler head having a substantially flat face and a pin projecting at right angles to the face and to one side of the center and a recess in the face to the other side of the center, the pin and recess arranged to cooperate with the recess and pin respectively of a cooperating coupled head to prevent relative lateral movements of the heads, the pin having a pocket, a transversely slidable locking member positioned within the head between the pin and recess and arranged to engage the wall forming the pocket in the pin of the cooperating head to hold the heads coupled, the locking member having a portion projecting into the recess in the coupler face to be engaged by the pin on a counterpart head in coupling to automatically retract the locking member, a spring operating to advance the locking member to enter the pocket in the pin on the counterpart head, un-

locking mechanism associated with the head and locking member to move the locking member to its unlocking position and means partially concealed within the coupler head to manually operate the unlocking mechanism.

25 9. A coupling device comprising in combination a recessed head having a transversely disposed front wall, a pin projecting from the wall and having a flat face and an aperture, a recess in the wall spaced from the pin and arranged to receive the pin of a counterpart coupler, a sliding lock positioned within the head between the pin and recess and movable transversely of the longitudinal axis of the pin and extending parallel to and adjacent the said wall and extending transversely to the axis of the recess and into overlapping relation to the recess to engage the wall of the aperture in the pin of the counterpart coupler, means pivotally mounted within the recess of the head to move the lock to its unlocking position and spring means arranged to advance the lock to its locking position and means projecting from the head to secure the coupler to an anchorage.

30 10. A coupling mechanism comprising in combination a coupler head having a substantially flat face and a pin projecting at right angles to the face and to one side of the center and a recess in the face to the other side of the center, the pin and recess arranged to cooperate with the recess and pin respectively of a cooperating coupled head to prevent relative lateral movements of the heads, the pin having a pocket opening on the side toward the recess, a transversely slidable locking member positioned between the pin and recess arranged to engage the wall of the pocket in the pin of a cooperating head to hold the heads coupled, the locking member having a portion projecting into the recess in the coupler face to be engaged by the pin on a counterpart head in coupling to retract the locking member, a spring arranged to advance the locking member to enter the pocket in the pin on the counterpart head, the engaging surfaces of the pocket wall and of the locking member being beveled to draw the heads together and hold them against relative longitudinal movement and unlocking mechanism associated with the head and locking member to move the locking member to its unlocking position.

35 11. A coupling mechanism comprising in combination a hollow head, a hollow pin projecting from a transverse wall at the front end of the head, a recess in the wall spaced from the pin to receive a pin on a counterpart head, an aperture in one wall of the pin opening into the hollow of the pin, a sliding lock parallel with the said wall and within the head between the pin and recess and arranged to enter the aperture in the pin of a counterpart head to hold the heads coupled, a spring acting upon the lock to urge the pin to enter the aperture of the counterpart head, the engaging surfaces of the pin and lock being beveled to cause the heads to be drawn together, means to move the lock counter to the spring and means projecting rearwardly from the head to secure the head to an anchorage.

40 12. A coupling mechanism comprising in combination a hollow head, a pin projecting from the head and having an aperture, a recess in the head spaced from the pin and arranged to receive the pin of a counterpart coupler, the aperture opening towards the recess, a sliding lock movable transversely of the longitudinal axis of the

pin and positioned between the pin and recess and extending into overlapping relation to the recess to engage the wall of the aperture in the pin of the counterpart coupler, the engaging surfaces on the sliding lock and aperture wall on the pin being beveled to coact together to draw the heads of two cooperating heads into tighter engagement and hold the heads in engagement, yielding means to move the lock to its locking position and means to move the lock from its locking position in opposition to the said yielding means.

13. In a car coupler, the combination with a hollow head having a transversely disposed face and fluid pressure connecting means, of a pin projecting from the face to one side of the vertical center line of the face and a recess in the face to the other side of said line, an opening in the pin, means on the head to engage the pin on the counterpart coupler to hold the heads and fluid pressure connecting means thereon in coupled relation and comprising a sliding lock positioned to the front of the head between the pin and recess and having a tapered projecting part adapted to enter the opening in the pin of the counterpart head and draw the heads and connecting means together, a spring to urge the lock to enter the said opening and means on the head to engage the lock to move the lock to its uncoupling position.

14. A coupling device comprising in combination a head, a hollow pin projecting from the head and having an aperture opening into the chamber in the pin, a recess in the head spaced from the pin and arranged to receive the pin of a counterpart coupler, a sliding lock positioned within the head between the pin and recess and extending transversely to the axis of the recess and into overlapping relation to the recess to engage the wall of the aperture in the pin of the counterpart coupler, means to move the lock to its unlocking position and means projecting from the head to secure the coupler to an anchorage.

15. A coupling mechanism comprising in combination a head having a substantially flat face, a pin projecting from the face to one side of the center thereof and a recess in the face to the other side of said center, the pin and recess arranged to cooperate with the recess and pin respectively of a cooperating coupled head to prevent lateral relative movement of the heads, a pocket in the pin, a transversely slidable lock member positioned within the head between the pin and recess and arranged to engage the wall forming the pocket in the pin of the cooperating head to hold the heads coupled, the lock member having a portion projecting into the recess in the coupler face to be engaged by the pin on the cooperating head to retract the lock member during coupling, a spring arranged to advance the lock member to its coupling position and unlocking mechanism associated with the lock member and the coupler head acting to move the lock member to its unlocking position against the tension of said spring.

16. In combination a pair of couplers having hollow heads with abutting flat faces, the heads having engaging pins and recesses to prevent relative transverse movement of the couplers, a transversely slidable lock mounted in each head to coact with means on the pin of the counterpart coupler to prevent the couplers separating and the coacting pins and locks having coacting wedging means to exert a drawing of the coupler

faces towards each other after the heads are coupled, spring means acting upon each lock tending to move it to its locking position and to aid in said drawing of the coupled heads towards each other and each head provided with means to move the locks on both coupled heads at will of an operator to their uncoupled position.

17. In combination a pair of connecting devices having hollow heads with abutting flat faces and cooperating fluid connections, the faces having recesses and also projecting pins to enter the recesses of the counterpart coupler and maintain the heads against transverse relative movement, a transversely slidable lock mounted within each head and arranged to coact with the pin of the coupled head to hold the heads and fluid connections against separation and pivotally mounted means within each head and each means cooperating with the locks on both heads to move the locks on both heads to their uncoupling positions, spring means to yieldingly hold the locks in their locking position, a pneumatically operated piston positioned in a cylinder associated with each head and arranged to act upon the said pivotally mounted means to effect the uncoupling of the heads, means to conduct air to each cylinder to operate the piston and means remote from the coupler to control the flow of air to the cylinder.

18. In a coupling apparatus of the type comprising a pair of coupling devices each comprising a vertically yielding hollow head with a flat face, the face having a recess and a projecting pin to enter the recess on the counterpart head and hold the heads against transverse and rotatable movement relative to each other, a movable lock mounted within each head and arranged to coact with the pin of the coupled head to hold the heads against separation; means to actuate the lock to effect uncoupling comprising pivotally mounted means within each head coacting with the lock therein to move the lock to its unlocking position, spring means to yieldingly hold each lock in its locking position, a support slidably mounted within each head and projecting therefrom, a second support for each said first support and to which the projecting portion of the first support is pivotally secured, a spring interposed between each head and its first support to resist but not prevent the uncoupling of the heads, means on the first support within each head coacting with the pivotally mounted means to operate the same, only when the movement of the head in one direction relative to the first support exceeds a predetermined amount, and counterpart car-coupling means to which the second supports are secured to prevent the relative longitudinal movement of the heads exceeding the said predetermined amount while the car-coupling means on which the two coupled heads are mounted are in coupled relation and yielding means supporting the front end of each head from the car-coupling means.

19. A coupling device for cars comprising in combination a head having a substantially flat face and a train line connection adjacent its face to cooperate with the connection on a counterpart device, a hollow pin projecting from the head and having an aperture opening into the chamber in the pin, a recess in the head spaced from the pin and arranged to receive the pin of the counterpart coupling device, a sliding lock positioned within the head between the pin and recess and extending transversely to the axis of the recess and into overlapping relation to the

recess to engage the wall of the aperture in the pin of the counterpart coupler and extend into the chamber of said pin to hold the heads and train line connections in coupled relation, means to move the lock to its unlocking position and having a portion extending into the chamber of the pin on the counterpart device to engage the end of the lock therein and means projecting from the head to mount the coupler on a car.

5 20. In combination, a pair of counterpart couplers, each having a hollow head with a front face and train pipe connecting means, the said means to engage like means on a counterpart head when coupled, a pin projecting from each 10 face to one side of the vertical center line and provided with a side opening, a recess in each face to the other side of the vertical center line and opening into the head to receive the pin from

the counterpart head, means on each head for holding the heads and train pipe connecting means in coupled relation, the said holding means comprising a horizontally slidable lock mounted between the pin and recess and having one end 5 arranged to project in overlapping relation to said recess and to enter the opening in the pin of the counterpart coupler and hold the heads and train pipe connecting means from separating, a spring acting on each lock to urge it to 10 enter the pin opening of the counterpart head and unlocking means on each head acting directly on the lock of each head independently of aid from the unlocking means on the counterpart head to move the locks on both coupled 15 heads to their unlocked position to allow the heads and connecting means to separate.

CHARLES H. TOMLINSON.
